(57) **CLAIM**

The ornamental design for a utility enclosure locking mechanism as shown and described.

DESCRIPTION

FIG. 1 is a front right top perspective view showing an embodiment of the utility enclosure locking mechanism of Applicant's new design.

FIG. 2 is a front left bottom perspective view of the utility enclosure locking mechanism of FIG. 1.

FIG. 3 is a front elevation view of the utility enclosure locking mechanism of FIG. 1.

FIG. 4 is a front right top perspective view showing another embodiment of the utility enclosure locking mechanism of Applicant's new design.

FIG. 5 is a front left bottom perspective view of the utility enclosure locking mechanism of FIG. 4.

FIG. 6 is a front elevation view of the utility enclosure locking mechanism of FIG. 4.

FIG. 7 is a front right top perspective view showing another embodiment of the utility enclosure locking mechanism of Applicant's new design.

FIG. 8 is a front left bottom perspective view of the utility enclosure locking mechanism of FIG. 7; and,

FIG. 9 is a front elevation view of the utility enclosure locking mechanism of FIG. 7.

The dash-dash broken lines in the drawings illustrate portions of the utility enclosure locking mechanism which form no part of the claimed design.

The dash-dot-dash broken lines in the drawings illustrate environment of the utility enclosure locking mechanism which form no part of the claimed design.

1 Claim, 6 Drawing Sheets
